CALCULATING MACHINE AND THE LIKE

Bengt Carlström and Roy Hanson, Atvidaberg,
Sweden, assignors to Aktiebolaget Facit, At-
vidaberg, Sweden, a joint-stock company of
Sweden

Application August 17, 1937, Serial No. 159,483
In Germany August 18, 1936

15 Claims. (Cl. 197—89)

The chief object of this invention is to create a very simple and reliable tabulating device for calculating machines and the like.

Another object of this invention is to render the tabulating device in such machines very compact.

Another object of this invention is to render the locking means for preventing incorrect manipulation very simple.

10 Another object of this invention is to render the ordinary locking rail and locking pawl or arm superfluous.

Other objects of this invention will be evident from the following specification and claims.

15 One embodiment of this invention is illustrated in the annexed drawing.

Fig. 1 shows a front view of a tabulating device in accordance with this invention.

Fig. 2 is a vertical section on the line II—II in 20 Fig. 1.

Fig. 3 is a section on the broken line III—III in Fig. 2.

The machine shown may be constructed, in its principal features, for instance, as shown and described in United States Patent application, 25 Serial No. 431,872, filed by Karl Viktor Rudin on February 27, 1930 (see German Patent No. 535,576), and United States Patents No. 1,927,771 and 2,068,899. However, in every multiplying 30 machine the results register and its actuator must be moved in relation to each other and analogously the quotient register and its operator must be moved in relation to each other (cf. the United States Patent application Serial 35 No. 756,823, filed on December 10, 1934). For this reason tabulating means are necessary in all such machines. Also in modern ten-key adding machines tabulating means are often used.

Referring now to the drawing, 1 indicates a dis- 40 placeable carriage which is guided for rectilinear motion on two shafts 2 which are rigidly secured to the stationary frame 3 of the calculating machine.

In the carriage 1 a shaft A is journalled which 45 in well-known manner carries a totalizer, for instance a results register or a quotient register or both, or an actuator, such as a pin wheel or Odhner rotor, a selector, etc., therefor. If the totalizer is on the carriage, the actuator is sta- 50 tionary, at least during the calculating operations, and vice versa, as well-known in the art.

On a shaft 4, which is also stationarily se- 55 cured to the frame 3, two step-tabulating keys 5 and 6 are rockably journalled, having each an oblong slot 7a through which a stationary shaft

7 extends. The shaft 7 limits the motion of the keys in both directions. The keys are retained in their positions of rest by means of tension springs 8. On pins 9 of the keys pawls 10 and 11 are pivotally mounted which are pressed against the side surface of a toothed wheel 13 by tension springs 12. The ends of the tension springs 12 are attached to pins 12a on the pawls and to pins 12b on the keys, respectively. The key 5 has the pawl 10 and the key 6 carries the pawl 11.

10 The gear wheel 13, which is rotatably mounted on the shaft 13a in the machine frame, has a number of pins 14, five of them being provided in the embodiment illustrated. The wheel 13 meshes with another toothed wheel 15 having two dia- 15 metrically opposed pins 16. The wheel 15 is journaled on the stationary pin 15a on the machine frame. The ratio of gear of the wheels 13 and 15 is so chosen that a rotary motion of the wheel 13 through an angle corresponding to the pitch 20 of the pins 14, i. e. one-fifth of a revolution, or 72° causes the wheel 15 to rotate through an angle corresponding to one-half revolution, or 180°.

The pins 16 engage a toothed rack 17 which 25 is pivotally mounted on the pin 18 of the carriage 1. Adjacent to the ends of the rack 17 rigid abutments 19 are provided on the carriage, said abutments projecting at right angles to the row of teeth of the rack. The tabulating keys 5 and 6 each have a projecting arm 20 which on the depression of the key is moved upwardly to engage a pin 21 on a lever 22. This lever is pivotally mounted on the fixed shaft 23 and provided with a pin 24 extending at right angles to the pin 21 and engaging the rack 17 from above. The arm 22 is also provided with a projection or lug 25 adapted to engage a recess in the disk 26 se- 30 cured on the shaft 27 which may be the main or driving shaft of the machine or a shaft posi- 35 tively connected with the driving shaft for rotation with the same. In a manually operated machine, the shaft 27 may be the handle or crank shaft, on which the actuator is journalled. In a power-driven machine the shaft 27 may be 40 a shaft driven by the motor, such as shaft 5 in U. S. Patent No. 2,068,899. The pin 24 is pulled into engagement with the top portion of the rack 17 by a tension spring 28, whose lower end is 45 secured to the pin 28a on the machine frame.

At their rear ends the keys 5 and 6 are provided with curved portions or cams 29 bearing on a lever 300 which is pivotally mounted on the sta- 50 tionary pin 30 in the machine frame and has two 55

projections 31 and 32 in engagement with the cams 29.

At its upper end each cam 29 has a recess 29a engaged by the projection 31 or 32, respectively, if the lever 300 is swung correspondingly.

About a pin 37 on the carriage 1 a double-armed lever 33 is pivotally mounted. At its upper free end this lever carries a handle 34 or the like, while the lower end of the lever carries a pin 35 entering a recess 36 of the rack 17. The recess 36 is angular, that is has two inclined surfaces along which the pin 35 is adapted to slide.

The device described operates as follows:

When one of the tabulating keys is depressed, for instance, the right hand key 6, the corresponding pawl 11 is lifted and engages the adjacent pin 14, so that this pin and thus the gear wheel 13 are rotated through an angle corresponding to the pitch of the pins, which is 72°. Consequently, the wheel 15 will be rotated half a revolution causing the pins 16 to move the toothed rack 17 and thus also the carriage 1 one step, that is a distance corresponding to the pitch of teeth of the rack 17, to the right in Fig. 1. The toothed rack 17 then yields accordingly, that is, it is swung somewhat upwards. Towards the end of this motion of the key the abutment 20 strikes against the pin 21 and, with the aid of the spring 28, forces the lever 22 to swing clockwise in Fig. 2, so that the pin 24 forces the rack 17 down into its lowermost or locking position. When a tabulator key is depressed and the rack 17 is raised or swung upwards as a result thereof it swings the lever 22 accordingly, causing the projection 25 to enter the recess of the disk 26, so that the main shaft 27 of the machine cannot be rotated, while tabulation is being effected. Tabulation having been terminated, the disk 26 is released in the manner indicated above when the lever 22 is swung in a clockwise direction.

Upon depression of the tabulating key 6 the corresponding cam 29 will actuate the projection 32, so that the projection 31 is swung in against the rear side of the pawl 10 and thus moves the latter out of the way of the adjacent one of the pins 14. At the same time, the projection 31 engages the recess 29a of the key 5, so that the latter is locked and cannot be depressed.

When the tabulator key 5 is depressed the carriage will be tabulated in an analogous manner step-by-step to the left, the pawl 11 being then pressed out of the path of the adjacent pin 14 through the action of the arm 32. Total tabulation for division is effected by means of the arm 33 which, when actuated, by its pin 35 lifts the rack 17 from the pins 16. The carriage may be displaced directly by means of the handle 34 in any direction, because the pin 35 then slides on the corresponding oblique surface of the recess 36 and lifts the rack 17.

Certain modifications may be made in the devices illustrated and described, without departing from the principle of this invention. Thus, the arm 33 may be operated from a special total tabulating or division key. The projections 19 at the ends of the row of teeth of the rack 17, which serve to limit the tabulation by preventing the wheel 15 from rotating, when the end of the tabulating motion in both directions has been reached, may be arranged on the frame of the machine.

It is to be observed that the tabulating rack 17 also serves to keep the carriage in its position when tabulation does not take place. This renders the special locking bar superfluous which is

ordinarily used, and which is provided with a series of recesses, one for each tabulating position, adapted to be engaged by a slide or an arm that must be brought out of engagement every time when a tabulation is to be made.

What we claim is:—

1. In a tabulating device for a calculating machine and the like, in combination, a rectilinearly movable carriage, a disk, pins on said disk, means for rotating said disk step-by-step, and a toothed rack on said carriage meshing with at least one of said pins, said rack being movable at an angle to the rectilinear path of motion of said carriage, while still remaining in mesh with one of said pins.

2. In a tabulating device for a calculating machine and the like, in combination, a rectilinearly movable carriage, a disk, pins on said disk, means for rotating said disk step-by-step, and a toothed rack on said carriage meshing with at least one of said pins, said rack being journaled on said carriage and rockable between a position parallel with the rectilinear path of said carriage and a position at an angle to said path, and reversely, while still remaining in mesh with one of said pins.

3. In a tabulating device for a calculating machine and the like, in combination, a rectilinearly movable carriage, a disk, pins on said disk, means for rotating said disk step-by-step, and a toothed rack on said carriage meshing with at least one of said pins, said rack being displaceable on said carriage substantially in parallel to itself and at an angle to the rectilinear path of said carriage, between a position of rest and an off-normal position, while still remaining in mesh with one of said pins.

4. In a tabulating mechanism for calculating machines and the like, in combination, a carriage displaceable in a rectilinear path, a stationary pivot, a disk rotatably journaled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and a restoring member for restoring said rack to its position of rest.

5. In a tabulating mechanism for calculating machines and the like, in combination, a carriage displaceable in a rectilinear path, a stationary pivot, a disk rotatably journaled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and a restoring spring for restoring said rack to its position of rest and for counter-acting its motion from said position of rest.

6. In a tabulating mechanism for calculating machines and the like, in combination, a carriage displaceable in a rectilinear path, a stationary pivot, a disk rotatably journaled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and a restoring spring for restoring said rack to its position of rest and for counter-acting its motion from said position of rest.

position and back again, while still remaining in mesh with one of said pins, and a main driving shaft carrying a locking disk, said locking disk having a recess in the path of a part of said lever to be engaged thereby, when said lever is rocked by said rack.

- 5 7. In a tabulating mechanism for calculating machines and the like, in combination, a carriage displaceable in a rectilinear path, a stationary pivot, a disk rotatably journalled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, a lever having one of its ends in engagement with said rack to be swung thereby, 15 a restoring spring for said rack engaging said lever, a main driving shaft, and a locking disk secured to said main driving shaft, a recess in said locking disk being in the path of motion of a part of said lever, when said rack is in its off-normal position.

- 20 8. In a tabulator for calculating machines and the like, in combination, a carriage displaceable in a rectilinear path, a rotary disk, pins on said disk, a manually operated key, a pawl on said key, said pawl being operatively connected with said disk for rotating the latter step-by-step upon manual actuation of said key, a toothed rack on said carriage meshing with at least one of said pins, said rack being movable at an angle to the rectilinear path of said carriage, while still remaining in mesh with one of said pins, and a lever having one of its ends in engagement with said rack, a part of said lever being in the path of motion of said key to be engaged thereby near the end of the stroke of said key.

- 25 9. In a tabulator for calculating machines and the like, in combination, a carriage movable on straight guides, a rotary disk, pins on said disk, manually operated keys, pawls on said keys, said pawls being operatively connected with said disk for rotating the latter stepwise upon manual actuation of said keys, a toothed rack on said carriage meshing with at least one of said pins, said rack being movable at an angle to said guides, while still remaining in mesh with one of said pins, cams on said keys, and a double-armed lever in engagement with said cams, said pawls being in the path of motion of said lever to be alternatively put out of operation thereby.

- 30 10. In a tabulator for calculating machines and the like, in combination, a carriage movable on straight guides, a rotary disk, pins on said disk, manually operated keys, pawls on said keys, said pawls being operatively connected with said disk for rotating the latter stepwise upon manual actuation of said keys, a toothed rack on said carriage meshing with at least one of said pins, said rack being movable at an angle to said guides, while still remaining in mesh with one of said pins, cams on said keys, said keys having recesses at one end of said cams, and a double-armed lever in engagement with said cams, said recesses being in the path of motion of said lever to lock one key, when another is depressed.

- 35 11. In a tabulator for calculating machines and the like, in combination, a straight guide, a car-

riage movable along said guide, a first toothed wheel, pins on said first wheel, a toothed rack on said carriage meshing with at least one of said pins, said rack being movable at an angle to said guide, while still remaining in mesh with said pins, a second toothed wheel in mesh with said first wheel, projections on said second wheel, manually operated tabulating keys, pawls on said keys normally engaging two of said projections in opposite directions of rotation of said second wheel, cams on said keys, and a double-armed lever in engagement with said cams, said pawls being in the path of swinging motion of said lever to be alternately disengaged from said projections thereby.

40 12. In a tabulating mechanism for calculating machines and the like, in combination, a carriage displaceable in a rectilinear path, a stationary pivot, a disk rotatably journalled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and abutments at the ends of the row of teeth of said rack to limit the rotation of said disk.

45 13. In a tabulating mechanism for calculating machines and the like, in combination, a carriage displaceable in a rectilinear path, a stationary pivot, a disk rotatably journalled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and abutments secured to said carriage adjacent to the ends of the row of teeth of said rack to limit the tabulation in both directions.

50 14. In a tabulating mechanism for calculating machines and the like, in combination, a carriage displaceable in a rectilinear path, a stationary pivot, a disk rotatably journalled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, and means for moving said rack out of engagement with said pins.

55 15. In a tabulating mechanism for calculating machines and the like, in combination, a carriage displaceable in a rectilinear path, a stationary pivot, a disk rotatably journalled on said pivot, pins on said disk, manually operated means for rotating said disk step-by-step, a toothed rack on said carriage meshing with at least one of said pins, said rack being movable at an angle to the rectilinear path of said carriage from a position of rest to an off-normal position and back again, while still remaining in mesh with one of said pins, a manually operated lever journalled on said carriage, and a pin on said lever engaging an angle-shaped recess in said rack.
